(57) **CLAIM**

The ornamental design for a display screen or portion thereof with graphical user interface as shown and described.

DESCRIPTION

FIG. 1 is a front view of a first embodiment of a display screen or portion thereof with graphical user interface showing the new design; and,

FIG. 2 is a front view of a second embodiment of a display screen or portion thereof with graphical user interface showing the new design.

The outermost broken lines in the figures show a display screen or portion thereof, and form no part of the claimed design. The other broken lines in the figures show portions of the graphical user interface that form no part of the claimed design.

Additional images and embodiments of a display screen or portion thereof with animated graphical user interface are shown and described in the Appendix filed herewith, the entire contents of which are hereby incorporated by reference.

1 Claim, 2 Drawing Sheets

FIG. 1
